UNITED STATES PATENT OFFICE.

OSCAR L. NEANDER, OF AURORA, NEBRASKA.

SPOUT LOCK.

Application filed August 11, 1923. Serial No. 658,980.

To all whom it may concern:

Be it known that I, OSCAR L. NEANDER, a citizen of the United States, residing at Aurora, in the county of Hamilton and State of Nebraska, have invented certain new and useful Improvements in Spout Locks, of which the following is a specification.

This invention relates to improvements in devices for locking the grain spouts of threshing machines in positions of adjustment. Various devices have been proposed for this purpose but ordinarily they are of a positive nature and clearly and positively lock the spout in positions of adjustment so that it is necessary to release a latch or some other equivalent locking element in order to adjust the spout. As the spout must be adjusted frequently, this type of locking means is an inconvenient one and generally unsatisfactory. Furthermore, such devices are liable to become broken due to the strains imposed thereon, thereby necessitating repairs and replacement. It is, therefore, one of the important objects of the invention to provide means for holding a grain spout in position of adjustment, which means will permit of the spout being swung to any desired position without the necessity of manipulating any mechanical parts and which will at the same time securely and firmly hold the spout in any position to which it is adjusted. The device embodying the invention is in the nature of a friction lock designed to hold the spout in various positions of adjustment and at the same time permit of the spout being swung from one position to another without the necessity of manipulating any mechanical locking elements, as above stated, and another important object of the invention is to so construct the device that the same may be adjusted to offer a greater or less degree of resistance to swinging movement of the spout.

In the accompanying drawings:

Figure 1 is a side elevation of the device embodying the invention, installed, parts being shown in section to better illustrate the structure;

Fig. 2 is a horizontal sectional view on the line 2—2 of Figure 1;

Fig. 3 is a vertical transverse sectional view on the line 3—3 of Figure 1;

In the drawings, the numeral 1 indicates

in general the grain spout of a threshing machine, and the numeral 2 indicates the discharge spout of the elevator from which the grain is discharged into the spout 1. The usual form of spiral conveyer is arranged within the spout 1 and as it does not constitute a part of the present invention, is not illustrated. This conveyor however embodies the usual shaft, which is indicated by the numeral 3 and upon which is fixed a sprocket gear 4 having a sprocket chain 5 trained about it, the chain passing also about a sprocket gear 6 fixed upon a shaft 7 mounted in a suitable bearing frame 8 beneath the intake end of the spout 1. This frame 8 also mounts the usual short vertical shaft 9 upon which is fixed a bevel gear 10 in mesh with a bevel gear 11 upon the shaft 7. A bevel gear 12 is also fixed upon the shaft 9 and is driven from a similar gear 13 upon a shaft 14, which shaft 14 is in turn driven from any suitable source of power supply.

The numeral 15 indicates a fixed part of the frame structure of the threshing machine, and bolted or otherwise secured thereto are the ends of an open annular friction band indicated by the numeral 16. The band 16, as will be observed by reference to Figures 1 and 2 of the drawings, is concentric to the shaft 9 and consequently concentric to the axis about which the spout 1 is to be angularly adjusted. The locking means for coaction with the friction band 16 is indicated in general by the numeral 17 and the same includes two collars 18 and 19 which are clamped or otherwise secured upon the spout 1 in spaced relation. A bracket 20 is secured to the under side of the collar 18 and is provided with an opening indicated by the numeral 21, and a similar bracket 22 is secured to the under side of the collar 19 and has a squared opening 23 formed therein. The numeral 24 indicates in general a thrust member in the form of a rod which is of rectangular cross section throughout a portion of its length indicated by the numeral 25, and throughout the remainder of its length is of cylindrical form and threaded as indicated by the numeral 26. The squared portion 25 of the thrust member is slidably fitted through the opening 23 in the bracket 22, and the threaded portion 26 is slidably fitted through the opening 21 in the bracket 20.

The squared portion 25 of the thrust rod is provided at its inner end with a friction shoe indicated by the numeral 27, and this shoe engages frictionally against the outer 5 side of the friction band 16 as clearly shown in Figures 1 and 2 of the drawings, having its engaging face curved to conform to the curvature of the said band. The numeral 28 indicates in general a second thrust member 10 which comprises a bar 29 having one end upturned right angularly as at 30 and supporting a friction shoe indicated by the numeral 31, this shoe bearing against the inner face of the said band 16 and being 15 located directly opposite the shoe 27. A bracket 32 is secured upon the upper side of the bar 29 and has a rectangular opening 33 slidably receiving the squared portion 25 of the thrust member 24, and the outer 20 end of the said bar 29 is upturned at right angles, as indicated by the numeral 34 and is formed with an opening 35 slidably receiving the threaded portion 26 of the said thrust member 24. A spring 36 is disposed 25 upon the threaded portion of the thrust member 24 and bears at one end against the upturned end 34 of the bar 29 and at its other end against a washer 37 which in turn rests against a nut 38 adjustably 30 threaded onto the portion 26 of the thrust member 24.

From the foregoing description of the invention and by reference to the drawings it will be understood that the two thrust members 24 and 28 are supported for relative sliding movement upon the spout 1 and that their respective shoes 27 and 31 engage 35 respectively against the outer and inner faces of the band 16. It will further be evident that the spring 36 exerts a thrust in 40 an outward direction upon the member 28 to hold the shoe 31 firmly against the inner side of the band 16 and at the same time exerts a thrust in an inward direction 45 against the member 24 to hold the shoe 27 firmly in engagement with the outer side of said band 16. Thus the two shoes bear with a greater or less degree of firmness frictionally against the faces of the band, and 50 this degree of pressure may be varied by adjusting the nut 38. Thus the shoes may be caused to bear relatively lightly against the band so as to permit of more or less free swinging movement of the spout 1, or, 55 by adjusting said nut 38 to further tension the spring 36, the shoes may be caused to bear with a considerable degree of force against the faces of the band and render movement of the spout more difficult. In 60 any event, by exerting the required degree of force, the spout 1 may be swung about its axis of adjustment to assume any desired position, and when released will be more or less securely held in its position of adjustment. 65

Having thus described the invention, what is claimed as new is:

1. The combination with a delivery spout supported for angular adjustment about a fixed axis, of a fixed friction member concentric to the axis, and yieldable means operatively connected with the spout frictionally engaging the said friction member. 70

2. The combination with a delivery spout supported for angular adjustment about a fixed axis, of a fixed friction member concentric to the axis, and friction shoes movable with the spout and engaging the inner and outer sides of the said member. 75

3. The combination with a delivery spout supported for angular adjustment about a fixed axis, of a fixed friction member concentric to the axis, friction shoes movable with the spout and engaging the inner and outer sides of the said member, and a single spring 80 acting to yieldably hold both shoes in engagement with the said friction member. 85

4. The combination with a delivery spout supported for angular adjustment about a fixed axis, of a fixed friction member concentric to the axis, a member slidably supported upon the spout, a shoe carried by the member and engaging one side of the friction member, a member mounted slidably upon the spout supported member, a shoe carried by the last mentioned member and engaging the other side of the friction member, and a single spring acting between the spout supported and last mentioned members for yieldably holding the shoes in frictional engagement with the said friction member. 90 100

5. The combination with a delivery spout supported for angular adjustment about a fixed axis, of a fixed friction member concentric to the axis, a thrust member slidably supported upon the spout, a shoe carried by the thrust member and engaging one side of the friction member, a thrust member slidably supported upon the first mentioned thrust member, a friction shoe carried by the second mentioned thrust member and frictionally engaging the other side of the friction member, abutments upon the thrust members, and a spring interposed between the abutments and urging the said thrust members in opposite directions. 110 115

6. The combination with a delivery spout supported for angular adjustment about a fixed axis, of a fixed friction member concentric to the axis, a thrust member slidably supported upon the spout, a shoe carried by the thrust member and engaging one side of the friction member, the said thrust member having a threaded portion, a second thrust member slidably supported with relation to the first mentioned thrust member, a shoe upon the second mentioned thrust member for frictional coaction with the other side of the friction member, an abutment upon the 120 125 130

second mentioned thrust member, a nut adjustably threaded onto the threaded portion of the first mentioned thrust member, and a spring interposed between the abutment and the nut and urging the thrust members in opposite directions.

7. The combination with a delivery spout supported for angular adjustment about a fixed axis, of a fixed friction member concentric to the axis, brackets upon the spout, one of said brackets having a non-circular opening, a thrust member of non-circular contour in cross section throughout a portion of its length and having said portion slidably fitted in the opening in the said bracket, the said thrust member having the other portion of its length threaded and slidably fitting the other bracket upon the spout, a shoe upon the thrust member frictionally engag-

ing one face of the friction member, a second thrust member having a portion provided with a non-circular opening slidably receiving the non-circular portion of the first mentioned thrust member, an abutment upon the second mentioned thrust member at one end, a shoe upon the said second mentioned thrust member at the other end frictionally engaging the other side of the friction member, a nut threaded onto the threaded portion of the first mentioned thrust member, and a spring arranged upon the said threaded portion of the first mentioned thrust member and bearing at one end against the abutment and at the other end against the nut.

In testimony whereof I affix my signature.

[L. s.]

OSCAR L. NEANDER.
